HAND TRUCK

Ernest Y. Takitani, Wailuku, Maui,
Territory of Hawaii

Application March 16, 1951, Serial No. 215,942

4 Claims. (Cl. 214—65.4)

1

This invention relates to hand trucks, and more particularly to a hand truck for handling loaded beverage bottle cases.

It is among the objects of the invention to provide an improved hand truck for beverage bottle cases which will carry a stack of loaded bottle cases and will pick up, carry and release the bottom case of a stack without the use of a pallet or platform for supporting the bottom case above a floor; which has operator actuated means for engaging and releasing the bottom case, which means is resiliently operated to firmly secure the bottom case to the truck while the cases are being moved; which independently supports all of the cases carried thereby and deposits such cases in an evenly stacked condition; and which is simple and durable in construction, economical to manufacture and easy to use.

Other objects and advantages will become apparent from a consideration of the following description and the appended claims in conjunction with the accompanying drawing, wherein:

Figure 1 is a rear elevational view of a hand truck illustrative of the invention;

Figure 2 is a fragmentary cross-sectional view on an enlarged scale on the line 2—2 of Figure 1;

Figure 3 is a cross-sectional view on the line 3—3 of Figure 2; and

Figure 4 is a fragmentary cross-sectional view similar to Figure 2, but showing the parts in different operative positions from that illustrated in Figure 2.

With continued reference to the drawing, the truck comprises a U-shaped frame 10, preferably formed of suitable metallic tubing bent to shape, and including a pair of spaced apart and substantially parallel legs 11 and 12, and an arcuately curved bight 13 joining the ends of the legs at one end of the frame and constituting a handle for the truck.

The legs 11 and 12 are arcuately curved at their ends remote from the bight 13 in a direction away from a plane including the center lines of the straight portions of the legs and the center line of the bight portion or handle, and an axle 14 extends transversely of the frame at the ends of the legs remote from the bight 13. This axle is secured to the legs by suitable clips 15 and 16 surrounding the axle and secured one to each of the legs at the corresponding ends of the legs.

Wheels 17 and 18 are journaled on the axle one at the outer side of each of the legs 11 and 12 and a pair of leg extensions 19 and 20 extend from the straight portions of the legs adjacent the curved, axle receiving portions thereof in a direction away from the bight of the frame and

2

with their center lines substantially in the above-mentioned plane including the center lines of the straight portions of the legs and the center line of the bight 13. These leg extensions have a length such that their distal ends rest upon a floor supporting the wheels 17 and 18 when the frame is disposed in substantially vertical upright position, as illustrated in Figure 2, the leg extensions then constituting continuations of the straight portions of the legs past the outwardly curved portions of the legs to the floor.

A plurality of substantially straight lift arms 21 project outwardly from the legs 11 and 12 at one side of the frame and have a length substantially equal to the width of the bottle cases, as indicated at 22 and 23. These lift arms are each connected at one end to the corresponding frame leg, are disposed substantially perpendicular to the frame legs and are arranged in pairs of which the two arms of each pair are carried one by each of the frame legs and are disposed at substantially the same distance from the distal ends of the corresponding leg extensions 19 and 20, so that the pairs of lift arms have their upper surfaces disposed in planes which are spaced apart longitudinally of the frame and are substantially parallel to the axle 14 and to each other. The distance between each two adjacent pairs of lift arms is substantially the same as the height of a loaded bottle case, as illustrated in Figure 1, so that a plurality of loaded bottle cases can be carried in relatively stacked position on the lift arms of the frame.

With wheeled hand trucks now in use for moving stacks of loaded bottle cases, the bottom case of the stack must either be supported on a pallet or platform so that the lowest pair of lift arms of the truck can be run under this bottom case, or otherwise, if the bottom case is placed directly on the floor, the operator must bodily pick up this bottom case and place it on top of the stack after the cases in the stack above the bottom case have been moved away from the bottom case by the truck, or must pick up the bottom case during a subsequent trip.

The provision of pallets or platforms requires an additional expense and is undesirable because these pallets or platforms take up additional space and are in the way when not supporting a stack of bottle cases. Picking up and moving the bottom case bodily by the operator is also wasteful of time and labor and is highly inconvenient if it is necessary to make a special trip with the hand truck to pick up the bottom cases from several stacks.

The present invention provides an improved hand truck which will pick up the bottom case of

the stack and carry it along with the remaining cases of the stack at the time the stack is moved, and does not require any platform or pallet for supporting the bottom case.

Bearing blocks 25 and 26 are mounted on the outwardly curved portions of the legs 11 and 12, one bearing block being mounted on each leg at the side thereof remote from the corresponding leg extension 19 or 20, and these blocks are spaced along the legs at substantially equal distances from the axle clips 15 and 16. A shaft 27 is journaled at its ends in the bearing blocks 25 and 26, and is normally disposed above and substantially parallel to the axle. Lever arms 28 and 29 project radially outwardly from the shaft 27, one near each of the bearing blocks 25 and 26, and these lever arms have their center lines substantially in a common plane which also includes the center line of the shaft 27.

Links 30 and 31 are connected each at one end to the lever arms 28 and 29, respectively, at the distal ends of these lever arms, and the links extend from the distal ends of the corresponding lever arms past the legs of the frame and adjacent the lift arms 21 of the lowest pair of lift arms.

Guides 32 and 33 are secured to and depend from the two lift arms of the lower pair of lift arms intermediate the length of the lift arms and at substantially the same distance from the corresponding frame legs 11 and 12. These guides slidably received the links 30 and 31, and the links are provided at their ends remote from the lever arms 28 and 29 with downwardly directed hooks, as indicated at 34, for the link 31.

Coiled tension springs 35 and 36 are connected between the links 30 and 31, respectively, and the adjacent leg extensions 19 and 20, and these springs resiliently urge the corresponding links to their raised position, as illustrated in Figure 4, wherein the corresponding lever arms are disposed between the shaft 27, and at least one lever arm engages a stop 42 on the corresponding frame leg. When the links are thus retracted, the corresponding guides 32 and 33 support the links so that the hooks at the free ends of the links are disposed above the upper edges of the walls and partitions of the bottom bottle case 23, as illustrated in dotted lines in Figure 4, and the springs 35 and 36 are disposed above the corresponding links, resiliently holding the links in their raised position.

Blocks or pads of resilient material, as indicated at 37, are secured one to each of the frame leg extensions 19 and 20 at the sides of the frame legs remote from the axle 14 and in opposition to the hooks 34 carried at the forward ends of the links 30 and 31.

A foot pedal 38 projects upwardly from the shaft 27 between the lever arms 28 and 29 when the links are raised and retracted. When the truck is moved up to a stack of bottles, the hooks 34 pass over the upper edges of the side walls and partition walls of the bottom bottle case, as illustrated in Figure 4. When the truck has been moved against the bottle cases, and the lift arms 21 slide under the bottoms of the corresponding cases of the stack above the bottom case, the foot pedal 38 is pressed down, rotating shaft 27, and the hooks 34 will drop into contact with the adjacent side of the upper portion of one of the partitions of the bottom bottle case.

As illustrated in Figures 2, 3 and 4, the partition engaged by the hooks is indicated at 40 and is parallel to the axle 14 and adjacent the side

wall of the bottle case remote from and parallel to the axle.

When the hooks are engaged with the partition wall 40, the arms 28 and 29 extend upwardly from the shaft 27, the springs 35 and 36 are below the corresponding links and urge the links downwardly and toward the frame, and a second foot pedal 41 projects upwardly from the shaft 27.

The second foot pedal 41 projects outwardly from the shaft 27 at a location between the lever arms 28 and 29, and is angularly spaced from the foot pedal 38.

The bottom case is now secured to the truck and the springs have sufficient strength to firmly compress the portion of the bottom bottle case between the resilient pads 37 and the hooks 34 and support the weight of this case from the hooks and the pads. The truck may now be tilted backwardly, lifting all of the bottle cases of the stack including the bottom case, and may be wheeled with the load of bottle cases to a different location, the distal ends of the leg extensions 19 and 20 being now disposed above the floor supporting the wheels.

In order to release a load of bottle cases from the truck at a desired location, the pedal 41 is pressed to advance the links and release the hooks from the partition wall 40. As shaft 27 is turned, arms 28 and 29 are moved back to their position below the shaft lowering the arm connected ends of the links and raising the hooks to release the partition wall 40 of the bottom case. As the arms are swung from their upper to their lower position, the links are first moved forwardly away from the frame so that the hooks are freed from the partition wall 40 as they are raised. After the hooks have been freed from this partition wall, the links are moved rearwardly toward the frame and below the springs 35 and 36, so that the springs now hold the links retracted with the hooks raised, as explained above.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A hand truck for handling loaded bottle cases comprising a U-shaped frame having spaced apart and substantially parallel legs and a bight portion joining the legs at one end of the frame and constituting a handle for the truck, an axle extending across said frame at the other end thereof and disposed substantially perpendicular to both of said legs and connected thereto, wheels journaled on said axle one adjacent each frame leg, said legs being curved at their axle connected ends away from the plane of the center lines of said legs and said bight portion, leg extensions extending from the curved portions of said legs with their center lines substantially in said plane and having their distal ends positioned to rest upon a floor supporting said wheels when said frame is in substantially vertical position, lift arms projecting outwardly from said legs at one side of said frame and arranged in pairs with the two arms of each pair connected one to each of said legs, said pairs

of lift arms having their surfaces remote from said axle disposed in planes substantially parallel to said axle and to each other and spaced apart to receive loaded bottle cases thereon, bearing blocks mounted one on each of said legs adjacent said axle and at the side of said frame remote from said lift arms, a shaft extending transversely of said frame and journaled in said bearing blocks, arms projecting radially from said shaft at spaced apart locations along the shaft and between said bearing blocks, links pivotally connected one to each arm at the distal ends of the arms and extending from said arms past said frame legs, each of said links being connected at one end to the corresponding arm and having a hook at its other end, guides secured one to each lift arm of the lower pair of lift arms and slidably receiving said links, springs connected one between each link and the adjacent leg extension urging said links to a retracted position in which said hooks are raised above the top edge of a bottom bottle case, a pedal on said shaft for raising said hooks so that said links may move in either direction across the top of a floor supported bottle case, a second pedal on said shaft for advancing said links and lowering said hooks to a position to engage a partition wall of a bottom bottle case, said springs moving said hooks into engagement with such a partition, and pads of resilient material secured one on each of said leg extensions in opposition to said hooks.

2. A hand truck for handling loaded bottle cases comprising a U-shaped frame, an axle extending transversely of said frame at the open end of the latter, means securing said axle to said frame at a location spaced from a plane including the center lines of the frame, wheels journaled on said axle one near each end thereof, lift arms projecting from said frame at the side thereof remote from said axle and arranged in pairs spaced apart longitudinally of the frame, a shaft journaled on said frame adjacent and substantially parallel to said axle, lever arms projecting radially from said shaft at spaced apart locations therealong and in the same direction, links secured one to each lever arm at the distal ends of the lever arms, said links being secured each at one end to the corresponding lever arm and extending respectively along the lift arms of the pair of lift arms adjacent the open end of the frame, a hook on the other end of each link, guides connected one to each lift arm of the pair of lift arms adjacent the open end of the frame and slidably receiving the adjacent links, springs connected one between each link and said frame for retracting said links, foot pedals on said shaft for manually advancing said links against the force of said springs, and pads on said frame in opposition to said hooks for contacting one side of a bottle case engaged by said hooks.

3. A hand truck for handling loaded bottle

cases comprising an elongated frame, an axle extending transversely of said frame at one end of the latter, means securing said axle to said frame at a location spaced from one side of the frame, wheels journaled on said axle one near each end thereof, a pair of lift arms projecting from the other side of said frame adjacent said one end thereof, a shaft journaled on said frame adjacent and substantially parallel to said axle, lever arms projecting radially from said shaft at spaced apart locations therealong and in the same direction, links secured one to each lever arm at the distal ends of the lever arms, said links being secured each at one end to the corresponding lever arms and extending respectively along the adjacent lift arms, a hook on the other end of each link, guides connected one to each lift arm and slidably receiving the adjacent links, springs connected one between each link and said frame resiliently retracting said links with said hooks, in either raised or lowered position, foot pedals on said shaft for manually raising said hooks and advancing said links against the force of said springs to release said hooks from a wall of a bottle case and for lowering said hooks into engagement with a bottle case wall, and pads on said frame in opposition to said hooks for contacting one side of a bottle case engaged by said hooks and connecting such a bottle case to said truck for movement thereby.

4. A hand truck for handling stacks of loaded bottle cases comprising a U-shaped frame, an axle disposed transversely of said frame adjacent the open end of the latter, means securing said frame to said axle with the axle spaced from one side of the frame, wheels journaled on said axle one at each end thereof, lift arms projecting substantially perpendicularly from the other side of said frame at a location along the latter to engage under the bottom of the case immediately above the bottom case of a stack of bottle cases to lift all of the cases in the stack above the bottom case, hook means mounted on said frame below said lift arms and projecting from said other side of the frame to releaseably engage the bottom case of a stack of bottle cases, and operator control means mounted on said frame and connected to said hook means for engaging said hook means with and releasing it from the bottom case of a stack of bottle cases.
